UNITED STATES PATENT OFFICE.

PETER D. KEYSER, OF PHILADELPHIA, PENNSYLVANIA, ASSIGNOR TO P. H. SHERIDAN, U. S. A., TRUSTEE, OF WASHINGTON, DISTRICT OF COLUMBIA.

DESIGN FOR A BADGE.

SPECIFICATION forming part of Design No. 18,393, dated June 19, 1888.

Application filed December 29, 1887. Serial No. 258,517. Term of patent 14 years.

To all whom it may concern:

Be it known that I, PETER D. KEYSER, a citizen of the United States, residing in the city and county of Philadelphia, State of Pennsylvania, have invented and produced a new and original Design for a Badge, of which the following is a specification, reference being had to the accompanying drawings, forming part thereof.

10 The leading feature of my design for a badge is a rosette having a face with sector-shaped sections and a rim with segmental sections on its face.

15 In the drawings, Figure 1 shows a side elevation, and Fig. 2 a plan view, of the badge.

A represents a rosette, which in the present case constitutes the head of a button. On the

face of the body of the rosette are sector-shaped sections *a b c*. The rim *A'*, which circumscribes the rosette, has segmental stripes *d e f* 20 on its face and oblique stripes *g h j* on its side.

I claim—

1. A design for a badge, consisting of a rosette with sector-shaped sections and a rim with segmental stripes on its face and stripes 25 on its sides, as shown and described.

2. In a design for a badge, the face portion thereof, having a rosette with sector-shaped sections and a circumscribing rim with segmental stripes, as shown and described.

PETER D. KEYSER.
